United States Patent Office

Des. 208,928
Patented Oct. 17, 1967

208,928

CLOCK OR SIMILAR ARTICLE

William V. Judson, Westport, and Theodore G. Daher, Stratford, Conn., assignors to General Electric Company, a corporation of New York

Filed May 4, 1966, Ser. No. 2,162

Term of patent 7 years

(Cl. D42—7)

Fig. 1.

Fig. 2.

Fig. 5.

FIG. 1 is a front perspective view of a clock embodying our new design;

FIG. 2 is a top plan view thereof;

FIG. 3 is a front elevational view thereof;

FIG. 4 is a side elevational view thereof; and

FIG. 5 is a rear elevational view thereof.

We claim:

The ornamental design for a clock or similar article, substantially as shown.
